(57) **CLAIM**

The ornamental design for a charger, as shown and described.

DESCRIPTION

FIG. 1 is a perspective view of a first embodiment of a charger, showing our new design;

FIG. 2 is a top view thereof;

FIG. 3 is a left-side view thereof, a right-side view being a mirror image thereof;

FIG. 4 is a bottom view thereof;

FIG. 5 is a back view thereof;

FIG. 6 is a front view thereof; and

FIG. 7 is a perspective view of a second embodiment of a charger, showing our new design;

FIG. 8 is a top view thereof;

FIG. 9 is a left-side view thereof, a right-side view being a mirror image thereof;

FIG. 10 is a bottom view thereof;

FIG. 11 is a back view thereof; and,

FIG. 12 is a front view thereof.

The broken lines shown in the drawings are included for the purpose of illustrating environmental structure and form no part of the claimed design.
